UNITED STATES PATENT OFFICE

WILLIAM HAMANN, OF IRONDEQUOIT, OF NEW YORK, ASSIGNOR TO UNITED SHOE MACHINERY CORPORATION, OF PATERSON, NEW JERSEY, A CORPORATION OF NEW JERSEY

FINISHING MACHINE

Application filed July 27, 1927, Serial No. 208,828. Renewed November 26, 1928.

This invention relates to shoe-finishing machines and is herein illustrated as embodied in an edge-setting machine designed for burnishing the edges of shoe soles.

5 Edge-setting machines commonly comprise an oscillating rock shaft, the oscillations of which are transmitted to an edge-setting tool. Since the edge of a sole has in the shank a contour distinctly different from the contour 10 of the edge of the sole around the forepart, it is customary to provide an edge-setting machine with two differently shaped burnishing tools, one for use in the shank and the other for treating the forepart, these tools 15 being carried in a holder which may be released from the rock shaft for rotation to carry either one of the tools into operative position. In edge-setting machines of the 20 type disclosed in applications of Brice and Hamann, Serial No. 598,837, filed November 3, 1922, and of Ray, Serial No. 17,063, filed March 20, 1925, rotation-imparting means are provided for transforming the oscillations of the rock shaft into rotational movement 25 of the tool holder to carry the desired tool into operative position upon actuation of manually operable means effective to break the driving connection through which the tool holder is oscillated normally.

30 It is an object of this invention to provide an improved edge-setting machine of the type referred to which will be so organized that release of the tool holder for rotation to interchange the edge-setting tools may be effected still more rapidly, with a minimum of effort on the part of the operator, and without substantially disturbing the operator's balance.

To this end, as herein illustrated in accordance with the present invention, provision is made for effecting the release of the tool holder of an edge-setting machine of the type referred to by operator-controlled means effective both to release the tool holder and to impart to it an initial rotary movement in the

direction in which the tool holder will be carried by the rotation-imparting means, thereby providing for interchanging the tools very rapidly while at the same time making no disadvantageous demand upon the operator's time and energy. As illustrated, upon movement of a manually operable lever, the tool holder is moved relatively to the rock shaft to separate complementary locking members on the tool holder and rock shaft respectively, thereby releasing the tool holder for rotation and imparting to it a movement around the rock shaft in the direction in which it will be carried by the rotation-imparting means so that the rotary tool-interchanging movement is a continuation of the movement imparted by the unlocking means. Further to facilitate the tool-interchanging movement, a wiper is preferably provided to clean, and if desired to lubricate, the bearing 50 surface against which the tool holder turns. 55

Another feature of the invention resides in the provision of an improved mounting for tool heating means, illustrated as an electric heating unit, to insure such displacement of the heating unit if the operator bumps the unit either with his hand or with the work as will minimize the danger of injury either to the operator's hand or to the work. 60 65 70

These and other features of the invention are set forth in the following description in which reference is made to the accompanying drawings wherein,

Fig. 1 is a side elevation partly in section of the end of the shaft of an edge-setting machine embodying the present invention, showing the tool holder and associated mechanism,

Fig. 2 is a section on the line II-II in Fig. 1,

Fig. 3 is a bottom view looking upward toward the under side of the mechanism shown in Fig. 1,

Fig. 4 is a perspective view of the tool

holder of another embodiment of the invention,

Fig. 5 is a detailed view showing a portion of the means for releasing the tool holder in the embodiment shown in Fig. 4,

Fig. 6 is a side elevation, partly in section, of mechanism for imparting rotational movement to the tool holder of the embodiment shown in Fig. 4,

Fig. 7 is a detailed view showing a wiper for cleaning the flange or rim of a housing against which flange the tool holder rubs when rotated,

Fig. 8 is an exploded view of parts of the rotation-imparting mechanism shown in Fig. 6,

Fig. 9 is a horizontal section through the mechanism shown in Fig. 6, taken at the axis of the shaft,

Fig. 10 is a vertical section on the line X—X of Fig. 9,

Fig. 11 is a similar section on the line XI—XI of Fig. 9,

Fig. 12 is a sectional view similar to Fig. 11 with the parts in different positions and the outer casing removed, and

Fig. 13 is a detailed view showing a heating element for heating the tools in their lowest position.

Since the invention may be applied to various edge-setting machines the construction of which is well known, it has not been deemed necessary to illustrate the whole machine herein and consequently there is shown only the end of an oscillating rock shaft 10 which projects outwardly from a frame 12 of a machine which has mechanism for oscillating said shaft at a high rate of speed in a fashion common in such machines. Upon the outer end of this shaft is mounted a tool holder 14 having oppositely projecting arms 15 and 17 which are recessed to receive tool-holding plungers 16 having studs 18 for the support of sole edge-burnishing tools, such as the forepart and shank burnishing tools 20 (Fig. 1) and 21 (Fig. 4). These tool-holding plungers are mounted at an inclination to facilitate the presentation of the sole of a shoe to the machine. Each plunger is urged outward to a limit determined by a locking strip 22 by means of springs 24 so that the tools may yield under the pressure of the work. A sleeve 26 is interposed between the tool holder and the reduced hollow outer end 27 of the shaft 10 to minimize friction and to reduce wear, the tool holder being symmetrical with respect to the axis of the rock shaft and balanced to reduce vibration to a minimum.

The tool holder 14 is held locked to the shaft so that it may oscillate therewith by a spring 28, inserted in the hollow outer end of the shaft 10 and secured to a cross-pin 30 therein. This spring 28 is arranged to move the tool holder axially to bring it into locking engagement with the notched rim of a

cup-shaped housing 32. The housing 32 is firmly secured to the shaft 10 by means of a cross-bar 34 and the rim around the open outer end of the housing is turned outwardly to form a flange 36 which is recessed to provide oppositely disposed notches 38 having wear-resisting liners 40. At one side of each notch 38 the flange is cut back to form an inclined surface 39. The tool holder 14 is provided with a pair of similar wedge-shaped locking projections 42 which enter the notches 38 as the holder revolves. The inclined surfaces 39 guide the projections 42 into the notches 38 and prevent overrunning and, in coaction with the spring 28, they facilitate the tool-interchanging rotative movement of the tool holder 14. The projections 42 are arranged to fit in the correspondingly shaped recesses 38 in the housing and in their original condition do not bottom in said recesses, thus leaving a clearance so that a tight fit will be maintained as the parts wear. It should be noted that the meeting edges of the projections 42 and the liners 40 in the notches 38 are at right angles to the plane of rotation of the tool holder 14 so that they will contact positively when, at the end of the rotation of the tool holder 14, said projections 42 slip off the inclined surfaces 39 and enter the notches 38.

For the connection of the outer end of the spring 28 to the tool holder 14, a hollow plug 44 is provided which is received in the outer end of the sleeve 26 and which has a slot in which rests a cross-bar 46 to which the spring is secured. The head of the block 44 rests against a washer 48 which in turn rests on an anti-friction member in the form of a series of ball bearings 50 held in a suitable cage and these roll upon the surface of a hardened steel plate 52 on the tool holder 14. This arrangement allows the full force of the spring to be directed against the tool holder thereby tending to effect axial movement of the holder with respect to the shaft without twisting the spring or causing any undue friction between the spring and the tool holder. At the same time, the spring is concealed and protected by being received within the hollow end of the shaft. To release the tool holder 14 from locking engagement with the housing 32, it may be moved by means hereinafter described, acting to push the tool holder axially against the tension of the spring 28 and remove the wedge-shaped projections from the coacting notches.

When a tool holder 14 mounted as above described with reference to the housing 32, is released from locking engagement with the housing and hence with the shaft by axial movement of the tool holder against the tension of the spring 28, it may be rotated manually to carry one tool out of and the other into operative position although preferably, and as herein illustrated, it is ro-

tated through rotation-imparting means 51 within the cup-shaped housing 32. This means, which is of the type shown in the Ray application to which reference has been made above, comprises a one-way clutch, one part 53 (Fig. 2) of which is secured to the tool holder 14, while the cup-shaped housing 32 forms the other part. To facilitate assembling the machine, certain parts of the one-way clutch are formed as an assembly (shown in section in Figs. 1 and 2) which comprises a sleeve 54 which is cut away at its opposite sides to form tapered pockets for rolls 56 which constitute the moving locking members of the one-way clutch. These rolls 56 are urged into locking position for engagement with the machined inner surface 58 of the cup-shaped housing 32 by means of springs 60 acting through plungers 62. The moving parts just described are held in the assembly by means of a surrounding band 64 slotted to permit the engagement of the rolls 56 with the inner periphery of the cup-shaped housing. This band is received within an annular groove in the outer periphery of the sleeve 54 and is held against rotation with respect thereto by means of a lip 66 which engages a corresponding recess in the sleeve. Adjacent to the inner periphery of the sleeve and positioned as a chord thereof is a bar 68 which cooperates with a flattened face 70 of an inwardly projecting sleeve 72 upon the tool holder. An end cover 74 is provided which is held by rivets 76 to the sleeve 54 and holds in the assembly not only the moving rolls 56 and the spring parts but also the bar 68 and the band 64 as well. The parts just described constitute, therefore, an assembly which by reason of the cooperation of the bar shaft 68 with the flattened face 70 of the tool holder sleeve 72 is slidably engaged with the tool holder 14 for rotation therewith and which at the same time may be inserted within the hollow of the cup-shaped housing. The assembly is retained against axial movement with respect to said housing, while rotating therein to interchange the tools, by means of screw pins 78 held by lock washers and arranged to enter a narrow groove 80 in the outer periphery of the sleeve 54. There is thus provided a self-contained mechanism within and protected by the housing 32, by which the power of the machine itself is utilized for interchanging the tools, the mechanism acting to transform the cumulative oscillations of the shaft to a rotary movement of the tool holder. A cylindrical casing 82 is provided which may be bolted to the frame 12 of the machine to surround and protect the oscillating housing 32. This casing is notched at 84 in order not to interfere with the oscillating notched portion of the flange 36 of the housing 32 (Fig. 3).

In order to displace the tool holder 14 axially on the oscillating rock shaft to permit

its partial rotation under the actuation of the rotation-imparting means 51, contained within the cup-shaped housing 32 so as to effect a quick and easy interchange of the tools, there is provided an operator-controlled lever 86 which is pinned to the lower end of an upright shaft 88 journaled in suitable bearings upon the casing 82. The outer end of this lever may be provided with a suitable strike plate 90 (Fig. 4) and its forked near end 92 provides for the pivotal support of a roller 94. The shaft 88 is extended upwardly to a point above the notched housing 32 and provided with another lever arm 96 in the forked end 98 of which there is journaled another roller 100. These rollers are arranged to bear against similar but oppositely inclined surfaces 102 formed at the outer ends of projecting portions 42 on the arms 15 and 17 of the tool holder 14 so that by reason of the inclination of these surfaces and the action of the rollers 94 and 100 thereon, the actuation of the lever 86 is effective not only to move the tool holder out of locking engagement with the notches of the cup-shaped housing 32 but also simultaneously to impart a rotative movement to it. Thus, as the outward unlocking movement is effected, the tool holder 14 is also turned, in the direction in which it will rotate under the action of the rotation-imparting means 51 already described, as soon as the projections 42 on the tool holder are free from the notches 38 of the cup-shaped housing 32. The spring 28 while moving the tool holder 14 axially tends at the same time to cause the rollers 94 and 100 to find the lowest points on the inclined surfaces 102, considering the rolling movement along the inclined surfaces as a movement down hill, thereby aiding and effecting rotative movement in the direction in which the tool holder will be rotated under the action of the rotation-imparting means 51. A spring 104 (Fig. 3) is attached to the lever 86 to bias it to inoperative position and adjustable stops 106 and 108 are provided for limiting the range of movement of said lever. The initial movement thus imparted by the tool holder releasing means will be immediately continued by the rotation-imparting means and the tool holder carried to its next succeeding position.

Heat may be supplied to the burnishing tools by radiation from electric units 110 and 112 supported upon the arms of bifurcated brackets 114 and 116. The upper bracket is rigidly attached to the casing 82 by means of a hand screw stud 118 and the lower bracket 116 is supported at the end of an arm 119 (Fig. 3) attached to and extending horizontally from a sleeve 120 which surrounds another hand screw stud 122. The bracket 116 is carried at the lower end of the plate 117 upon which there is mounted a stud 121 passing horizontally through a cylindrical open-

ing at the end of the arm 119. The stud 121 is notched and is engaged by the reduced flat end of a plunger 124 (Fig. 13) pressed thereagainst by a spring 125, the tension of which may be adjusted by means of a screw 127. This plunger 124 acts, therefore, to return the bracket 116 to its normal depending relation in case it is accidentally displaced and also serves to prevent accidental removal of the stud 121. It will be noted that the sleeve 120 is provided with a handle 123 (Fig. 3) so that the operator may, when removing and replacing a tool, swing the heating unit support around the vertical axis of the screw stud 122 to an inoperative position and then return it to initial position when the tool has been replaced. A spring member 133 (Fig. 1) serves to prevent too free swinging movement around the screw stud 122. This method of supporting the lower unit 112 permits its rotation around either an upright axis or a horizontal axis so that if the operator accidentally bumps into the unit either with his hand or with the work, the unit will be readily pushed aside without danger of injury to either one. An attachment block 126 (Fig. 3) is provided for the connection of a source of supply of electric current to the flexible leads 128 by means of which current is transmitted to the heating units. It will be noted that a shield 130 is provided adjacent to the upper tool which shield is an extension of the bifurcated bracket 114 and serves not only to retain the heat supplied to the upper tool but also serves as a guard to prevent accidental contact with said tool.

As also in the similar form shown in Fig. 4, the flange 36 at the outer rim of the cup-shaped housing 32 forms a smooth surface upon which the inner ends of the wedge-shaped projections 42 ride. Since by reason of the action of the spring 28 upon the tool holder 14 there is a considerable pressure between the inner ends of these wedge-shaped projections and said flange it is desirable that the flange be cleaned and, preferably also lubricated, to reduce friction as much as possible. Accordingly, there is provided a wiper 132 (Fig. 7) supported in a holder 134 slidably mounted in a casing 136 attached to a lateral face of one of the projecting tool carrier arms 15 of the tool holder 14 to rotate therewith and, in so rotating, to clear the flange. Inward movement of this wiper 132 is limited by means of a stud 138 and nuts 140 as the wiper is pressed against the flange 36 by means of a spring 142. The wiper is illustrated as a piece of felt which serves to keep the flange 36 clean from dirt and, if it is saturated with oil, to lubricate the same. It will be understood that the wiper 132 may be applied either to the embodiment shown in Figs. 1 to 3 or to the embodiment about to be described which is shown in Figs. 4 to 6 and 8 to 12.

The embodiment of the invention which is illustrated in Figs. 4 to 6 and Figs. 8 to 12 includes certain parts which are substantially the same as the corresponding parts shown in Figs. 1 to 3. These parts have been given the same reference numerals and no further description of them will be necessary. It will be seen from Figs. 4, 5 and 6 that the tool holder 14 in this embodiment is rotatably mounted on the sleeve 26 surrounding the hollow outer end 27 of the shaft 10, and that it is provided with wedge-shaped projections 142 coacting with similarly shaped recesses 144 having liners 146 set into the flange 148 of a housing 150 secured to the shaft 10. This housing 150 is cup-shaped like the housing 32 and contains a rotation-imparting means 152 of the type shown in the Brice and Hamann application to which reference has been made above. When the tool holder 14 is released by pressure on the lever 86 against a spring 97 (Fig. 4) to produce axial movement of said holder to disengage the locking projections 142, it is rotated to interchange the tools by a spring 154 in which energy has been stored up through a one-way clutch by oscillation of the shaft 10. This spring 154 (Fig. 9) is connected at one end to a pin 156 projecting inwardly from the tool holder 14, and the other end of the spring 154 is secured by a screw 158 (Fig. 11) in a recess of a ratchet wheel 160 constituting part of a one-way clutch, the hub of said ratchet being swiveled on the sleeve 26 on the rock shaft 10. An advancing pawl 162 (Fig. 9) forming another part of said clutch is pivoted on a stud 164 (see also Fig. 11) in a slot of the cup-shaped housing 150 and is normally pressed by a spring 166 against the teeth of the ratchet wheel. This pawl can be intermittently brought into engagement with the ratchet teeth for brief intervals in order to rotate the ratchet and energize the spring or it may be rendered temporarily ineffective, by mechanism to be described, when sufficient energy has been stored up in the spring 154. A retaining pawl 168 is mounted on an eccentric stud 170 projecting (Fig. 9) from the frame of the machine, a spring 172 tending to hold the pawl always in engagement with the ratchet. The eccentric mounting provides means, as the mechanism is assembled, for varying the position of the pawl so that it will properly engage the teeth.

The ratchet wheel 160 has a smooth bearing sleeve or flange 174 (Fig. 8) extending inwardly to receive mechanism for rendering the advancing pawl ineffective including a swinging carrier 176 provided with opposite pairs of guide flanges 178 and 180 at diametrically opposite points. On the rear of the carrier is slidably mounted a plate 182 which is hollow, loosely to embrace the bearing sleeve 174 on the ratchet and is provided with a projection 184 and an opposing projection 186.

terminating in a cam 186, said projections being received between said flanges. A similar plate 188 having a projection 190 and an opposed projection terminating in a cam 192 is slidably mounted between the guide flanges 178 and 180 on the front of the carrier 176 and the two plates are normally impelled outwardly as far as the flanges permit by a spring 194 (Fig. 10) joining the arm 196 on the slide plate 182 with the arm 198 on the slide plate 188. Either of the cams 186 or 192 on the slide plates 182 and 188 (depending on the position of the parts) is adapted to lift the advancing pawl 162, as later described, by engagement with an inwardly projecting roll 200 (Fig. 11) thereon. Stop lugs 202 and 208 projecting from the rear side (Fig. 8) of the ratchet wheel 160 limit the relative rotational movement of the carrier 176 with respect to said ratchet in one direction, and similar stop lugs 204 and 206 limit the movement of the carrier in the opposite direction. The swinging carrier 176 with the two slide plates is normally kept at one limit of swinging movement, so that the cams rest against two opposite stop lugs on the ratchet, by a spring 210 (Fig. 10) connected to the carrier 176 and to the ratchet wheel 160. The slide plates and the carrier are held in assembled position between the ratchet wheel 160 and a washer 212 (Fig. 9) abutting against the hub of the cup-shaped member 150.

The cams 186 and 192 are employed (alternately and successively) for the purpose of raising the advancing pawl 162 from the teeth of the ratchet when the spring 154 is wound up. In the position shown in Fig. 11 the ratchet wheel is just beginning to advance under control of the pawl 162 and the oscillating shaft 10 with which the pawl is connected. As the cam 192, for example, moves around, it contacts with a roll 214 (Fig. 11) mounted on the pivot 164 of the advancing pawl. This contact temporarily arrests the movement of the cam 192 and hence the swinging carrier 176, the ratchet continuing to advance and the spring 210 stretching until the lug 202 reaches said carrier 176. Thereafter as the cam 192 is moved past the roll 214, contacting therewith, it is pushed inwardly so as to pass inside of said roll, the cam face causing the plate 188 to slide radially in its guides against the tension of the spring 194. As the cam passes the roll 214, it is suddenly pulled forwardly by the spring 210 against the stop lug 204 and outwardly by the spring 194 to engage the small roll 200 on the end of the advancing pawl 162 which is thereby raised suddenly from the teeth of the ratchet wheel by the percussive impact of cam 192. This action prevents any further rotation of the ratchet wheel or further winding of the spring 154. It should be noted that opposite portions of

the periphery of the ratchet wheel have the teeth interrupted for a short distance, thus insuring the stopping of the ratchet wheel after one half a revolution if for any reason the pawl tripping mechanism fails to operate. The ratchet wheel carries two opposite outwardly projecting stops 216 and 218 which lie in the same circle as the pin 156 projecting inwardly from the tool holder 14. After the parts have reached the position shown in Fig. 12, where the advancing pawl is shown out of engagement with the ratchet wheel, the tool holder may be released to interchange the tools. Thereupon, the tool holder, carrying the pin 156 which projects inwardly from it, is caused to rotate clockwise (as viewed in Fig. 12) by the spring 154 until the pin 156 engages the stop 216 on the ratchet, or the unwound spring pulls the ratchet wheel along forwardly to carry the cam 192 slightly ahead of and clear of the advancing pawl 162, which is thereby allowed to return again into engagement with the ratchet teeth to wind up the spring again in preparation for a subsequent interchange of tools. On the next interchange of tools, the corresponding cam 186 and associated parts operate in a similar manner.

Another mechanism is thus provided acting to the same end as that shown in Figs. 1 to 3 to secure a quick and easy interchange of the tools. Here the tool holder 14 is adapted, when released from the rock shaft 10 by depression of the manually operated lever 86 (Fig. 4), to be rotated through 180 degrees by means of a spring 154, one end of which is secured to the tool holder at 156, and the other end of which is secured to the ratchet wheel 160 by the screw 158. This ratchet wheel 160, which is held against reverse rotation by means of a retaining pawl 168 secured to the frame of the machine, is forwardly rotated intermittently, using the power of the machine itself, by means of the advancing pawl 162, which is secured to the rock shaft 10 by being mounted on the cup-shaped housing 150. The oscillations of the rock shaft cause the advancing pawl to move the ratchet wheel 160 along step by step until sufficient energy has been stored up in the spring 154 to effect a partial rotation of the tool carrier to interchange the tools. Inasmuch as the period of time required for this winding up of the spring will probably never exactly coincide with the period between the interchange of tools, mechanism has been provided, as above described, for rendering the advancing pawl 162 ineffective after the spring has been wound up until such a time as the tool holder has been given a partial rotation. This mechanism comprises the carrier 176, associated with which are two cam plates 182 and 188. These cam plates are normally spring-pressed outwardly by a spring 194, and their cam projections 186 and 192 lie between

projections on the ratchet wheel, being in the carrier 176 which is held against the projections 204 and 206, as shown in Fig. 10, by a spring 210. As the ratchet wheel is advanced step by step, the cam 192, for example, will be brought into contact with the roller 214 occupying a fixed position in the machine. This engagement will temporarily retard forward movement of the cams and their carrier until the abutment 202 on the ratchet wheel contacts with the back face of the guide flange 178 of the carrier 176 and forces the cam 192 past the roller 214. When this happens, the cam 192 will be depressed inwardly against the tension of the spring 194, and as it passes beyond the roller 214, the cam plate will be forced outwardly suddenly to raise the advancing pawl 162 from engagement with the teeth of the ratchet wheel. As the machine is operated, the arrangement thus far described will store up energy in the spring 154, so that when the releasing lever 86 is depressed by the operator, the tool holder will be carried around to bring the next tool into operative position. As the tool holder flies around, the unwound spring 154 will tend to drag the ratchet wheel and the cams along, to bring the cam 192 out of contact with the roller 200 on the advancing pawl 162, thus allowing this pawl to return into engagement with the ratchet wheel so that energy may be again stored up in the spring for the next interchange of tools. If the cam projection has not been moved in this fashion, then the pin 156 (Fig. 11) projecting inwardly from the back side of the tool holder will engage an outwardly projecting stop 216 or 218 on the ratchet wheel and carry the ratchet wheel around the shaft to push the cam projection 192 past the advancing pawl 162. There is thus provided a self-contained mechanism associated with the tool holder and concealed within the cup-shaped housing 150, which rotates about the axis of oscillation, and in the operation of which the tool holder is rotated by the power of the machine itself, the mechanism operating to transform the cumulative oscillating movements of the shaft 10 to a rotary movement of the tool holder or carrier 14.

Surrounding the housing 150 and secured to the main frame 12 is an auxiliary casing 220 (Figs. 4, 9 and 11) with upper and lower flat guide faces 222 (Fig. 11) for slides 224 (Fig. 4) guided and held in place by cover plates 226. On the slides 224 are mounted outwardly extending brackets 228 carrying electric heating units 110 and 112. The heating units lie parallel to the edge setting irons and out of contact therewith to heat them by radiation. To vary the degree of heat, the units can be moved toward or from the edge irons by levers 230 (Fig. 3) pivoted on a boss 232 on the auxiliary casing and loosely embracing pivot studs 234 (Fig. 4) project-

ing from the slides 224. To hold the slides frictionally in any position, springs are interposed between the levers and nuts on the ends of the pivot studs 234.

In the operation of either illustrated embodiment of the invention, the operator, whenever he desires to interchange the tools, will press against the strike plate 90 to actuate the lever 86 and will thereby cause axial movement of the tool holder to release its locking projections from the shaft. This movement will be accompanied by an initial rotational movement of the tool holder, as the latter is freed from the shaft, which movement will be immediately supplemented and continued by a rotational movement furnished by the rotation-imparting means 51 or 152 thereby to turn the tool holder through 180 degrees and bring the desired tool into operating position. Thus the interchanging of the tools may be accomplished very rapidly and without disturbing the operator's balance or distracting his attention.

Having described the invention, what I claim as new and desire to secure by Letters Patent of the United States is:—

1. A shoe finishing machine having, in combination, an oscillating rock shaft, a tool holder connected to the shaft to oscillate therewith, said tool holder being rotatably mounted on the shaft but normally held against rotating movement relatively to the shaft, means for releasing said tool holder for rotating movement relatively to the shaft, said last-named means being constructed and arranged to impart to the tool holder an initial rotary movement relatively to the shaft, and means for imparting to the tool holder a further rotary movement relatively to the shaft when the tool holder is released for such movement.

2. A shoe finishing machine having, in combination, an oscillating rock shaft, a tool holder connected to the shaft to oscillate therewith, said tool holder being rotatably mounted on the shaft but normally held against rotating movement relatively to the shaft, rotation imparting means for effecting rotating movement of the tool holder relatively to the shaft in a given direction when the tool holder is released for such movement, and means for releasing the tool holder for rotating movement relatively to the shaft constructed and arranged to impart to the tool holder an initial rotary movement in the direction in which the tool holder will be carried by said rotation imparting means.

3. A shoe finishing machine having, in combination, an oscillating rock shaft, a tool holder connected to the shaft to oscillate therewith, said tool holder being rotatably mounted on the shaft but normally held against rotating movement relatively to the shaft, a pair of finishing tools carried by said holder, rotation imparting means for effect-

ing rotating movement of the tool holder relatively to the shaft in a given direction to interchange the tools when the tool holder is released for such movement, and means for releasing the tool holder for tool interchanging movement constructed and arranged to impart to the tool holder an initial rotary movement in the direction in which the tool holder will be carried by said rotation imparting means.

4. An edge-setting machine having, in combination, an oscillating rock shaft, a tool holder connected to the shaft to oscillate therewith, said tool holder being rotatably mounted on the shaft but normally held against rotating movement relatively to the shaft, shank and forepart edge-setting tools carried by said holder, means for releasing said tool holder for rotating movement relatively to the shaft to interchange said tools, said last-named means being constructed and arranged to impart to the tool holder an initial rotary movement relatively to the shaft, and means for continuing said rotary movement of the tool holder to complete a tool interchanging movement.

5. In a shoe finishing machine, an oscillating rock shaft, a tool holder carrying a plurality of differently shaped tools rotatably mounted on said rock shaft and normally locked to the shaft for oscillation therewith as a shoe is presented to that one of the tools that is in operative position, means for releasing the tool holder for rotary movement relatively to the rock shaft constructed and arranged to impart to the tool holder an initial rotary movement relatively to the shaft, rotation imparting means energized by the rock shaft and constructed and arranged to continue the rotary movement of the tool holder initiated by said releasing means to bring a succeeding tool into operative position, and means for locking the tool holder on the shaft in that position.

6. In a shoe finishing machine, an oscillating rock shaft, a tool holder for a plurality of tools rotatably mounted upon said shaft, said tool holder having a bearing surface inclined to the axis of the shaft, a spring for urging said tool holder axially to lock it to the shaft, means for displacing said tool holder axially against the tension of said spring to release it for rotary movement relatively to the shaft, said means comprising a roller arranged to bear against said inclined bearing surface, whereby the energy of the spring tending to bring the roller to the bottom of the incline on the tool holder imparts to the tool holder an initial rotational movement, and means for imparting a further rotary movement to the tool holder with respect to the shaft to interchange the tools.

7. In a shoe finishing machine, an oscillating rock shaft, a tool holder for a plurality of tools rotatably mounted upon said shaft,

a spring for urging said tool holder axially to lock it to the shaft, means for displacing said tool holder axially against the tension of said spring to release it from the shaft for rotary movement relatively to the shaft, 70 said means being constructed and arranged to impart to the tool holder an initial rotary movement by reason of the combined action of the displacing means as it presses against the tool holder and the action of the spring 75 opposing said displacing means, and means for imparting a further rotary movement to the tool holder with respect to the shaft to interchange the tools.

8. In a shoe finishing machine, an oscillating rock shaft, a tool holder for a plurality of tools rotatably mounted upon said shaft, means for urging said tool holder axially to lock it to the shaft, means for moving said tool holder axially to release it from the shaft constructed and arranged to impart an initial, 80 rotational movement to the tool holder, and means for imparting a further rotary movement to the tool holder around the shaft 85 when it is released therefrom.

9. In a shoe finishing machine, an oscillating rock shaft, a tool holder rotatably mounted on said shaft and connected to the shaft to oscillate therewith, said tool holder having a bearing surface inclined to the axis of the shaft, means for releasing said tool holder for rotational movement relatively to the shaft, said means comprising a roller arranged to bear against the inclined bearing surface on the tool holder thereby to impart an initial rotational movement to the tool holder as it releases the same, and means for imparting rotational movement to the tool holder relatively to the shaft when the tool holder is released for such movement.

10. In a shoe finishing machine, an oscillating rock shaft, a tool holder rotatably mounted on said rock shaft, a notched member secured to said rock shaft, means for resiliently holding said tool holder in engagement with said notched member thereby to secure the tool holder to the rock shaft, and means for releasing said tool holder from engagement with said notched member comprising a lever and an inclined surface constructed and arranged to impart an initial rotational movement to the tool holder as it is released from engagement with the notched member.

11. In a shoe finishing machine, an oscillating rock shaft, a cup-shaped housing secured to said rock shaft and having its rim formed to provide a flange in which there is a notch, a holder for a plurality of tools rotatably mounted on the rock shaft and provided with a wedge-shaped projection adapted to enter said notch, means for holding said tool holder in engagement with the notch of said housing comprising a spring and an 120 125 130

- anti-friction member secured to said spring and bearing against said tool holder, and means for disengaging said tool holder from said notched housing against the tension of said spring.
- 5 12. In a shoe finishing machine, an oscillating rock shaft, a cup-shaped housing secured to said rock shaft and forming one of the members of a one-way clutch, a sleeve within said housing forming another member of said one-way clutch, a tool holder rotatably mounted on said rock shaft and movable axially on the shaft to engage said housing or to release the holder from the 10 housing, said tool holder being slidably engaged with but locked to the sleeve within said housing so that said sleeve rotates with the tool holder, and gripping members interposed between said sleeve and the inner 15 surface of said housing.
13. In a shoe finishing machine in which a tool holder is rotatably mounted upon the end of an oscillating rock shaft and movable axially thereof and which has a housing 20 provided with rotation imparting mechanism comprising a one-way clutch, an assembly forming one of the parts of said clutch and adapted to be held against axial movement in the housing, said assembly comprising locking members for the clutch, a sleeve cut away to receive the movable locking members, a bar extending along a chord of said sleeve slidably to connect said assembly with the tool holder to rotate therewith, and means for retaining said locking members and said bar in said assembly so 25 that the latter may be inserted as a unit into the housing on said shaft.
14. In a shoe finishing machine, an oscillating rock shaft, a cup-shaped housing secured to said rock shaft and provided with a flange around its rim, a tool holder rotatably mounted on said rock shaft and detachably interlocked with said housing, means 30 for resiliently holding said tool holder against said housing, means for releasing said tool from engagement with the housing, means upon the tool holder constructed and arranged to clean and lubricate said flange thereby to facilitate the rotation of the tool holder, and means for imparting a rotational movement to the tool holder after it has been 35 released from the housing.
15. In an edge-setting machine, a rock shaft, an oscillating setting tool on said rock shaft, an electric device for heating said tool by radiation, and means for pivotally supporting said device adjacent to said tool, said 40 means being constructed and arranged to allow the heating device to be displaced around an upright axis.
16. A shoe finishing machine having, in combination, an oscillating rock shaft, a tool holding member normally connected to the 45 rock shaft to oscillate therewith and carrying a plurality of differently shaped tools, and means for releasing the tool holder from the rock shaft to permit interchanging tools including an operator-controlled member adapted to be brought into engagement with said tool holding member to displace the same, one of said engaging members having an inclined surface whereby the pressure of the operator-controlled member against the tool holding member imparts an initial movement to the latter member tending to bring another tool into operative position.
17. A shoe finishing machine having, in combination, an oscillating rock shaft, a tool 50 holder carrying a plurality of differently shaped tools rotatably mounted on said rock shaft to permit bringing said tools successively into operative position, means for locking the tool holder to the shaft for oscillation therewith, and operator-controlled means constructed and arranged simultaneously to unlock the tool holder and to impart rotative movement thereto.
18. A shoe finishing machine having, in combination, an oscillating rock shaft, a flanged member mounted on said rock shaft, a tool holder carrying a plurality of differently shaped tools mounted to rotate about said rock shaft, interlocking means between the flanged member and the tool holder to hold the tool holder for oscillation with the rock shaft, resilient means urging said tool holder axially into locking engagement with the flanged member, and operator-controlled means for displacing said tool holder out of locking engagement with the flanged member, said operator-controlled means being constructed and arranged to impart a rotational movement to the tool holder relatively to the 60 flanged member.
19. A shoe finishing machine having, in combination, an oscillating rock shaft, a tool holder rotatably mounted on said rock shaft, a member secured to said rock shaft having a flanged portion extending around the rock shaft and provided with a plurality of recesses, resilient means urging the tool holder axially of the rock shaft to draw it into interlocking engagement with the recesses in said flanged member to cause the tool holder to oscillate with the rock shaft, said flanged member having inclined portions to facilitate the rotative movement of the tool holder, and operator-controlled means for lifting the tool holder out of a recess and setting it over upon the flanged portion for rotation along said flanged portion and subsequent engagement with another recess.
20. A shoe finishing machine having, in combination, an oscillating rock shaft, a tool holder mounted for rotation about said rock shaft, and means, including a spring, a member having an inclined surface and an operator-controlled device movable in opposition 70 75 80 85 90 95 100 105 110 115 120 125 130

to said spring, for imparting a rotational movement to said tool holder to bring another tool into operative position.

21. A shoe finishing machine having, in combination, an oscillating rock shaft, a tool holder carrying a plurality of differently shaped tools mounted on said shaft for rotation about the axis of said rock shaft and adapted to be secured thereto for oscillation with the shaft, a spring urging said tool holder axially into interlocked engagement with the shaft, and means for imparting a rotational movement to said tool holder comprising an operator-controlled device and a member having an inclined surface.

15 In testimony whereof I have signed my name to this specification.

WILLIAM HAMANN.
